DESIGN FOR A BOTTLE

René Durand, Paris, France, assignor to Lentheric, Incorporated, New York, N. Y., a corporation of New York

Application December 18, 1935, Serial No. 60,150

Term of patent 14 years

To all whom it may concern:

Be it known that I, René Durand, a citizen of France, residing at Paris, France, have invented a new, original, and ornamental Design for a Bottle, of which the following is a specification, reference being had to the accompanying drawing, forming part thereof.

In the drawing:

Fig. 1 is a top view of a bottle embodying my design;

Fig. 2 is a front view; and
Fig. 3 is a side view thereof.

I claim:

The ornamental design for a bottle substantially as shown.

In witness whereof I affix my signature.

RENÉ DURAND.
